(57) **CLAIM**

The ornamental design for a slip on shoe, as shown and described.

DESCRIPTION

FIG. 1 is a top left front perspective view of a left foot slip on shoe showing our new design;

FIG. 2 is a top view thereof;

FIG. 3 is a right side view thereof;

FIG. 4 is a front view thereof;

FIG. 5 is a left side view thereof;

FIG. 6 is a rear view thereof; and,

FIG. 7 is a bottom view thereof.

The objects shown in broken, phantom lines are shown for environmental purposes only and form no part of the claimed design.
